UNITED STATES PATENT OFFICE.

PETER ANGUS MCSWAIN, OF RALSTON, MISSISSIPPI.

DESIGN FOR A BIT-FRAME.

SPECIFICATION forming part of Design No. 34,345, dated April 9, 1901.

Application filed March 14, 1901. Serial No. 51,208. Term of patent 7 years.

To all whom it may concern:

Be it known that I, PETER ANGUS MCSWAIN, a citizen of the United States, residing at Ralston, in the county of Perry and State of Mississippi, have invented and produced a certain new and original Design for Bit-Frames; and I do declare the following to be a full, clear, and exact description of the invention, such as will enable others skilled in the art to which it appertains to make and use the same.

The invention relates to a new and original design for a bit-frame; and it consists of a design of the shape and configuration shown in the accompanying drawing, in which the invention is illustrated in perspective.

The leading features of the design comprise the body portion 1, having a central opening

2, the laterally-projecting sleeve 3, the downwardly-projecting sleeve 4, and a handle 5, projecting upwardly from said frame. The laterally-projecting sleeve has inclined ribs 6, and the downwardly-projecting sleeve is tapered outwardly from its lower end upwardly.

What I claim is—

The design for a bit-frame, as herein shown and described.

In testimony whereof I have hereunto set my hand in presence of two subscribing witnesses.

PETER ANGUS MCSWAIN.
